H. R. ROBBINS.

Burglar Alarm.

No. 21,849.

Patented Oct. 19, 1858.

UNITED STATES PATENT OFFICE.

HENRY R. ROBBINS, OF BALTIMORE, MARYLAND.

BURGLAR-ALARM.

Specification of Letters Patent No. 21,849, dated October 19, 1858.

To all whom it may concern:

Be it known that I, HENRY R. ROBBINS, of the city of Baltimore and State of Maryland, have invented a new and useful Improvement in Burglar-Alarms; and I do hereby declare that the following is a full, clear, and exact description of the same, reference being had to the accompanying drawings, forming a part of this specification, in

10 which—

Figure 1, is a front view of a door with my improved burglar alarm attached to it. Fig. 2, is an edge view of the same.

Similar letters of reference in each of the 15 several figures indicate corresponding parts.

The nature of my invention consists in the manner hereinafter specified of combining and arranging relatively to each other on a door and door frame, the alarm movement, cap-nipple, exploding spring hammer and stop or set pin, whereby simultaneously with the operation of setting the hammer so as to explode a cap when the door is opened the verge of the alarm movement is caused 20 to lock the verge wheel and thus prevent the running down of the spring and simultaneously with the opening of the door and the explosion of the cap, the verge wheel is unlocked and the alarm movement caused to 25 give a continuous alarm.

To enable others, skilled in the art, to make and use my invention, I will proceed to describe its construction and operation.

The alarm movement which I adopt is 30 very similar to an ordinary clock movement as will be evident from the drawing and therefore need not be particularly described. This movement A, B, C, M, N, is attached to a plate F, which is screwed to the top of a door G, on the inside of a sleeping room, or other place, as represented.

H, is the cap exploding hammer which I employ in connection with the alarm movement. This hammer is pivoted by its handle 40 to the plate F, in such a position relatively to the crack which exists between the top of the door and the door frame G¹ that it shall stand across said crack when set for operation and the door is closed.

I, is a link attached to the top part of the 50 hammer.

J, is a stop or set pin attached to the top piece of the door frame. On this pin the perforated end of the link I, catches when the door is closed and the hammer set for 55 operation as shown in black, said link and pin serving to hold the hammer in operative position.

K, is the cap nipple, it is arranged under the hammer and receives an explosive cap, 60 as represented.

L, is a wire connecting the cap exploding hammer with the verge A, of the alarm movement. This wire should have no slack so that when the hammer H, is raised and 65 set as shown in black, the verge shall be caused to lock the verge wheel B, and thus hold the spring C, from running down until the proper time for sounding the alarm arrives.

With the above arrangement and combination, it will be evident that if the spring C, is wound up, the verge wheel locked, and the cap exploding hammer set, when the door is opened, the cap exploding hammer 70 H, will descend and explode the cap and thus by its descent will, through the wire L, operate the verge and thereby unlock the alarm movement and allow it to operate the hammer M, of the alarm bell N, with a 80 quick continuous movement.

It is very important to have an alarm capable of producing a sudden explosive sound, and then to give a continuous alarm by means of a bell, as very many persons 85 cannot be aroused from a deep slumber by the sound of a bell, while most persons, will be instantly aroused by the sudden explosion of a cap or pistol. Hence it is, that in several instances, pistols or small cannons have 90 been used in connection with locks, hold-fasts, &c.

My invention differs from, and is superior to, the devices before used in its simplicity and utility, it being readily attached 95 to any door and costing very little more than an ordinary cheap clock movement, and serving to give a sudden start to the sleeper

when a burglar enters the room, and then keeping up a continuous alarm until he is fully aroused and made aware of his danger.

What I claim as my invention and desire 5 to secure by Letters Patent, is—

The manner herein specified of combining and arranging relatively to each other on a door G and door frame G¹ or other structure, the alarm movement, cap nipple K, ex-

ploding spring hammer H, and stop or set 10 pin J for the purpose set forth.

The above specification of my improvement in burglar alarms signed by me this 16th day of September, 1858.

H. R. ROBBINS.
